[57] CLAIM

The ornamental design for fireplace insert smoke pipe connector, as shown and described.

DESCRIPTION

FIG. 1 is a front perspective view of a fireplace insert smoke pipe connector, showing my new design;

FIG. 2 is a top plan view thereof;

FIG. 3 is a front elevational view thereof;

FIG. 4 is a side elevational view, the opposite side being a mirror image thereof;

FIG. 5 is a bottom plan view thereof;

FIG. 6 is a rear elevational view thereof;

FIG. 7 is a cross sectional view taken along line 7—7 of FIG. 2 and

FIG. 8 is an enlarged front perspective view thereof.

The broken line disclosure included in FIG. 1 is for illustrative purposes only and forms no part of the claimed design.
